TRAIL SHOE ASSEMBLY

Adolph P. Buquor, Washington, D. C., assignor to
 Martin-Parry Corporation, York, Pa., a corpora-
 tion of Delaware

Application August 23, 1943, Serial No. 499,666

8 Claims. (Cl. 89—40)

This invention relates to apparatus for preventing the digging in of a trail spade of an artillery piece or gun during firing thereof, and is primarily intended to be employed when the recoil shock of the gun during firing is absorbed by mechanism other than the spade or spades of the gun trail.

The trail spade shoes of the present invention thus find their major utility when employed in conjunction with firing platforms such as disclosed in my copending application, Serial No. 499,665, filed August 23, 1943. In such environments it is important to prevent the recoil of the gun from causing the spade of the trail to penetrate into the ground, since preventing the trail from digging into the ground maintains vertical alignment of the gun. Also, when the spade shoes of the present invention are employed it is unnecessary to withdraw the trail spades from the ground in order to make a rapid large angle traverse of the gun carriage. No modification of the trail or spade of a gun is required and the trail spades are left available for normal use when no firing platform is employed by merely removing the shoes.

It is, therefore, an object of the invention to provide a detachable shoe or platform for attachment to the spade on the trail of a gun to prevent it from digging into the ground.

Another object is to provide a shoe for the spade of a gun trail which may be left in position during transport of the gun.

A still further object of the invention is to provide a shoe or bearing member for the spade of a gun trail which enables the gun trail to be easily moved angularly about the center of the gun carriage.

Other objects and advantages of the invention will appear in the following description of preferred embodiments of the invention shown in the attached drawings, of which

Fig. 1 is a rear elevation of a shoe for a trail spade shown attached to one of the spades of a split trail gun;

Fig. 2 is a side elevation of the spade shoe of Fig. 1;

Fig. 3 is a side elevation of a modified form of trail shoe;

Fig. 4 is a plane view of the device of Fig. 3; and

Fig. 5 is a rear elevation of the device of Figs. 3 and 4.

Referring to Figs. 1 and 2, the trail shoe 10 shown therein preferably comprises a base member 11 of wood or other light weight structurally 55

strong material having an attaching member 12 suitably secured to the upper surface thereof adjacent the center of the body portion 11, by any suitable attaching means such as screws 13. The attaching member carries a front clamping member 14 suitably secured and braced upon the base 17 of the attaching member 12 by a bracing member 16. The base 17 may extend rearwardly and upwardly to form a rear clamping member 18 provided with a plurality of screw threaded apertures 19 receiving clamping screws 21 shown in Fig. 2. The clamping members 14 and 18 provide a slot 23 therebetween to receive the spade 24 of the gun trail and tightening of the clamping screws securely attaches the spade shoe to the spade. The body portion 11 of the spade shoe may also be provided with spade centering members 26 suitably secured to the upper surface of the ends of the body portion 11 by any means, such as screws 27. The centering members 26 are provided with inner upturned flanges 28 which are adapted to be engaged by the inclined bottom edges of the spade 24 to guide the spade laterally into the slot 23 of the clamping member 16.

The body portion 11 of the shoe is preferably provided with upwardly curved ends 29 to provide for easy movement of the shoe laterally of the gun trails so as to provide for rapid traversing of the gun. While only one spade shoe is shown in Figs. 1a and 2, it is to be understood that two will be provided for a split trail gun having another trail spade 31. For closing the trail, one of the shoes of the type shown in Figs. 1 and 2 must be removed from a spade such as the spade 31 and in this event one of the guiding members 26 provides a support for the spade 31 when the trails are closed.

The spade shoe of Figs. 3, 4 and 5 are however, 40 of small enough lateral extent to provide for closing the trails (not shown) of a gun with a shoe attached to each spade. The shoe of Figs. 3 to 5 preferably comprises a single metallic member 32 such as a casting or forging, but may be 45 obviously fabricated from separate pieces by welding, etc. The base portion of the shoe is preferably made in convex form having a hollowed out portion 33 containing a front clamping portion 34 suitably braced by a bracing portion 36 and a rear clamping portion 37 suitably braced by a bracing portion 38. The two clamping portions 34 and 37 provide a slot 39 therebetween for receiving the point of a spade 40. The rear clamping portion 37 is provided with a plurality of screw threaded apertures 41 receiving clamp-

ing screws 42 for securing the spade 39 in the slot 38. The lower surface of the shoe is preferably provided with a plurality of laterally extending ribs 43 providing for easy movement of the shoe and spade laterally of the spades, for example in making rapid large traverses of the gun carriage or opening or closing the trails of a split trail gun carriage. These ribs also, at least to some extent, resist recoil shock although the shoe prevents penetration of the spades into the ground.

It will be noted that the point of the spade in the slot 38 is positioned very close to the surface upon which the spade shoe rests and in this respect the shoe of Figs. 3 to 5 differs materially from the shoe of Figs. 1 and 2. Also, the shoe of Figs. 3 to 5 enables closing of the gun trails while the shoes are in position upon the spades so that the gun may be transported with the shoes in position, but these shoes have been found adequate in area to prevent substantial lowering of the gun trail during firing. The advantage of having the tips of the gun trail adjacent the ground is that this enables the gun trails to be supported in substantially the normal firing position of the gun and does not reduce the possible elevation of the gun.

While I have disclosed the preferred embodiments of my invention, it is understood that the details thereof may be varied within the scope of the following claims.

I claim:

1. A device for preventing digging of the trail spade of an artillery gun trail into the ground during firing of the gun, said device comprising a member providing a lower surface having a substantial area for contact with the ground, said member having an upwardly directed slot in its upper portion for receiving the spade and means engaging the spade to releasably clamp said member to the gun trail.

2. A device for preventing digging of the trail spade of an artillery gun trail into the ground during firing of the gun, said device comprising a member providing a lower surface having a substantial area for contact with the ground, said member having a front clamping member upon its upper portion and a rear clamping member positioned adjacent said front clamping member to provide a slot between said clamping members for receiving the spade of the trail, and means carried by one of said clamping members for releasably clamping the spade against said other clamping member.

3. A device for preventing digging of the trail spade of an artillery gun trail into the ground during firing of the gun, said device comprising a member providing a lower surface having a substantial area for contact with the ground, said member having an upwardly directed slot in its upper portion for receiving the spade and means to secure said member to the gun trail, said member having laterally disposed guiding portions at opposite sides of said slot for guiding the trail spade laterally into said slot.

4. A device for preventing digging of the spade of an artillery gun trail into the ground during firing of the gun, said device comprising a supporting member providing a lower surface having a substantial area for contact with the ground, said member having a front clamping member upon its upper portion and a rear clamping member positioned adjacent said front clamping member to provide a slot between said clamping members for receiving the spade of the trail, and means carried by one of said clamping members for clamping the spade against said other clamping member, said supporting member having laterally disposed guiding members at opposite sides of said slot for guiding the trail spade laterally into said slot.

5. A device for preventing substantial penetration of the trail spade of an artillery gun trail during the firing of the gun, which comprises, a member providing a lower surface having a substantial area for contact with the ground, said member having an upwardly extending slot for receiving the trail, said slot extending substantially to the lower surface of said member and means to clamp the spade in said slot.

6. In a device for preventing substantial penetration of the trail spades of an artillery gun trail during the firing of the gun, which comprises, a member providing a lower surface having a substantial area for contact with the ground, said member having an upwardly extending slot for receiving the trail, said slot extending substantially to the lower surface of said member and means to clamp the spade in said slot, said member having a plurality of laterally extending ribs on the lower surface thereof.

7. In a device for preventing substantial penetration of the trail spades of an artillery gun trail during the firing of the gun, which comprises, a substantially circular member providing a lower surface having a substantial area for contact with the ground, said member having an upwardly extending slot for receiving the trail, said slot extending substantially to the lower surface of the member and means to clamp said spade in said slot, said member having a plurality of laterally extending ribs on the lower surface thereof.

8. A device for preventing substantial penetration of the trail spade of an artillery gun trail during the firing of the gun, which comprises, a member providing a lower surface having a substantial area for contact with the ground, said member having an upwardly extending slot for receiving the trail, said slot also extending substantially to the lower surface of said member and means to clamp the spade in said slot, said member being substantially round in horizontal section and having a lower surface approaching that of a portion of a sphere, said member having a plurality of laterally extending ribs on its lower surface.

ADOLPH P. BUQUOR.
